(57) **CLAIM**

The ornamental design for a portable loudspeaker, as shown and described.

DESCRIPTION

FIG. 1 is a front, top, right perspective view of a portable loudspeaker according to the present invention;

FIG. 2 is a rear, top, right perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom view thereof; and,

FIG. 9 is a cross-section view taken through a handle of the portable loudspeaker, along line 9-9 of FIG. 2.

The dashed broken lines immediately adjacent the shaded areas represent the bounds of the claimed design while all other broken lines are included for the purpose of illustrating portions of the portable loudspeaker; all of the broken lines form no part of the claimed design.

1 Claim, 8 Drawing Sheets
